UNITED STATES PATENT OFFICE

171,737

SPLASH TROUGH

Decio Torricelli, Springfield, Mass.

Application April 3, 1953, Serial No. 24,337

Term of patent 14 years

(Cl. D18—2)

To all whom it may concern:

Be it known that, I, Decio Torricelli, a citizen of the United States, residing at Springfield, in the county of Hampden, and Commonwealth of Massachusetts, have invented a new, original, and ornamental Design for a Splash Trough, of which the following is a specification, reference being had to the accompanying drawing forming part hereof:

Fig. 1 is a top plan view of a splash trough showing my new design;

Fig. 2 is a side elevational view of the device shown in Fig. 1; and

Fig. 3 is an end elevational view of the device shown in Fig. 1.

I claim:

The ornamental design for a splash trough, as shown.

DECIO TORRICELLI.
